UNITED STATES PATENT OFFICE.

MICHAEL ANDES, OF WILKES-BARRE, PENNSYLVANIA.

BITUMINOUS-COAL FUEL.

No. 830,953.

Specification of Letters Patent.

Patented Sept. 11, 1906.

Application filed June 7, 1906. Serial No. 320,608.

To all whom it may concern:

Be it known that I, MICHAEL ANDES, a citizen of the United States, residing at Wilkes-Barre, in the county of Luzerne and State of Pennsylvania, have invented a new and useful Bituminous-Coal Fuel, of which the following is a specification.

My present invention relates to composite fuel, the object being to produce a fuel-body or briquet possessing the requisite stability or cohesion and so organized that while substantially bituminous in character it will burn without the excessive coking or caking which characterizes the burning of bituminous coal.

To the accomplishment of this object the invention consists in combining bituminous and anthracite coal slack and cement in proper proportions. As is well understood by those skilled in the art, bituminous coal when burned fuses or cakes into a tough coherent mass which obstructs the draft and cokes unless the mass is repeatedly broken. This peculiarity of bituminous coal is due to the fact that it is rich in volatile hydrocarbons, the heating of which renders the body of coal soft and adhesive.

Many efforts have been made to form fuel-bodies of bituminous-coal slack. Such bodies have either been combined with binders in a manner to produce an unstable structure which would readily crumble, or the composition has been such that the fuel would cake and coke in the manner of ordinary bituminous coal. As the result of a series of experiments I have found that by combining a comparatively small percentage of anthracite-coal slack with a comparatively large percentage of bituminous-coal slack in a body which is given the requisite stability by a small percentage of cement a free-burning fuel of excellent quality and one which will not coke or cake excessively when burned may be produced.

In preparing the fuel I thoroughly intermix the comparatively large quantity of bituminous-coal slack with the comparatively small quantity of anthracite-coal slack, the ratio being greater than two to one, and preferably about four to one. I then add and intermix a comparatively small quantity of Portland or other suitable cement, water being gradually added to the mass until it becomes sufficiently plastic to be spread on a suitable surface, where it is left to dry and

set. If blocks of regular size are desired, the material may be suitably scored before drying, or the layer when dried may be broken into lumps of suitable size for furnace use. Similarly, the mass instead of being spread upon a flat surface for drying, as heretofore stated, may be molded into any desired shape.

By reason of the preponderance of the bituminous-coal slack the fuel will have the general burning qualities of bituminous coal, but the objectionable fusing or caking will be materially reduced by reason of the incorporation of the hard anthracite particles throughout the structure, such particles forming separations between many of the bituminous particles or bodies which would otherwise contact with each other and readily adhere when heated. These anthracite particles furthermore improve the quality of the fuel for the reason that they are slow-burning and maintain a condition of incandescence for a longer period than the bituminous particles, thus causing the complete consumption of many of the bituminous particles which would otherwise be merely coked. It will therefore be seen that the predominance of the bituminous slack is material, since it is desired to secure a fuel which is primarily bituminous in character, but which will not possess the objectionable characteristics common to bituminous briquets. For instance, the volume of smoke liberated by the combustion of bituminous fuel will be greatly reduced, probably from one-third to one-half, while the briquets can be stored and transported in large quantities and in all kinds of weather without danger of spontaneous combustion, crumbling, or other disintegration. Attention is further directed to the fact that the cement not only lends stability to the fuel structure, but also opposes to a considerable degree the caking and consequent coking of the fuel, because it extends substantially throughout the mass and partially occludes the individual particles of coal. The percentage of cement is relatively small, being just sufficient to act as a binder for the particles without necessarily filling all of the interstices. The body of fuel will therefore be of more or less spongy or porous appearance and will burn freely until practically consumed.

In referring to both the bituminous and anthracite coal I have used the term "slack."

This term is to be accorded its ordinary meaning—to wit, "small coal," "coal dirt," or "screenings."

What I claim is—

- 5 1. A fuel-body consisting of a predominating quantity of bituminous-coal slack, a comparatively small quantity of anthracite slack, and a binder of cement, the quantity of bituminous slack being more than twice the quantity of anthracite slack.
- 10 2. A fuel-body consisting of a predominating quantity of bituminous-coal slack, a com-

paratively small quantity of anthracite-coal slack, the bituminous and anthracite slack being in substantially the proportion of four 15 to one, and a binder of cement.

In testimony that I claim the foregoing as my own I have hereto affixed my signature in the presence of two witnesses.

MICHAEL ANDES.

Witnesses:

JAMES L. LENAHAN,
C. B. LENAHAN.
